UNITED STATES PATENT OFFICE.

WILLIAM M. LEWIS, OF NORFOLK, VIRGINIA.

WAGON-JACK.

1,074,184.

Specification of Letters Patent. Patented Sept. 30, 1913.

Application filed April 25, 1913. Serial No. 763,683.

To all whom it may concern:

Be it known that I, WILLIAM M. LEWIS, a citizen of the United States, residing at Norfolk, in the county of Norfolk and 5 State of Virginia, have invented a new and useful Wagon-Jack, of which the following is a specification.

This invention relates to jacks for wagons, automobiles and the like, one of its 10 objects being to provide a novel form of jack constituting a part of the vehicle and which is normally held in inactive position under the body thereof, means being provided whereby, when the jack is released, 15 it will shift downwardly into engagement with the surface on which the vehicle is mounted so that, when the vehicle is drawn forward, the jack will operate to elevate the adjacent wheels off of the supporting surface. 20

A further object is to provide novel means whereby the jack is shifted positively into engagement with the supporting surface and held yieldingly in supporting position after the vehicle has been elevated. 25

A further object is to provide a jack which can be applied readily to the axle of a vehicle already in use.

With the foregoing and other objects in view which will appear as the description proceeds, the invention resides in the combination and arrangement of parts and in the details of construction hereinafter described and claimed, it being understood 35 that changes in the precise embodiment of the invention herein disclosed, can be made within the scope of what is claimed, without departing from the spirit of the invention.

40 In the accompanying drawings the preferred form of the invention has been shown.

In said drawings:—Figure 1 is a side elevation of a portion of a vehicle having a 45 jack applied to each axle thereof, the jacks being supported in inactive positions. Fig. 2 is a bottom plan view of the structure shown in Fig. 1. Fig. 3 is a section on line A—B Fig. 1. Fig. 4 is a view partly in side 50 elevation and partly in section of a portion of the vehicle, the rear jack being shown in supporting position while the front jack is shown lowered to the position assumed thereby immediately prior to the elevation 55 of the front end of the vehicle.

Referring to the figures by characters of

reference 1 and 2 designate the front and rear axles, 3 designates the supporting wheels, and 4 the vehicle body. Mounted to swing upon each of the axles 1 and 2 is a 60 bail-shaped jack 5 having terminal eyes 6 which extend loosely around the axle. The intermediate portion of each jack is preferably formed with prongs 7 adapted to engage the ground when the jack is lowered. 65 A coiled spring 8 is secured at one end to the vehicle body at a point back of the axle to which the jack is secured and this spring extends under the axle and is secured to the intermediate portion of the jack. Thus it 70 will be seen that when the jack is swung forwardly and upwardly upon the axle, spring 8 connected thereto will be elongated and it is therefore necessary to use a hook 9 or the like for engaging the jack to hold it elevated in inactive position. Stop fingers are extended downwardly from each axle, as shown at 10 and are extended laterally so as to project into the paths at the side portions of the jacks. These stop fingers are 80 provided so as to limit the swinging movement of the jacks when they are released from their holding devices 9.

When it is desired to elevate a vehicle, the fastening devices 9 are disengaged from the 85 jacks and the said jacks immediately swing downwardly so as to bring the prongs 7 into engagement with the ground, this movement being facilitated by the springs 8. The jacks thus each assume a position as shown at the 90 left of Fig. 4. By then pulling the vehicle forwardly, the jacks will be caused to swing about the lower ends thereof as centers, thus causing the lower ends to shift past their centers of gravity until the jacks come 95 against the stop fingers 10 where they will be held yieldingly by the springs 8. The vehicle will thus be held supported with its wheels out of contact with the ground, each jack assuming a position such as is shown 100 at the right of Fig. 4. Obviously by releasing only one of the jacks, the axle to which said jack is connected will be elevated while the wheels supporting the other axle will remain in contact with the ground. Importance is attached to the particular arrangement of the spring whereby the one spring exerts a constant pull upon the jack and serves not only to shift it downwardly 105 in contact with the ground but also to pull it rearwardly past its center of gravity and against the stop fingers 10. When it is de-

sired to reset the jacks, it is merely necessary to push the vehicle rearwardly so as thus to force the jacks past their centers of gravity whereupon the jacks can be swung upwardly so as to be reengaged by the fasteners 9. During this resetting of the jacks, the springs 8 are elongated and are partly wrapped about the axles.

It will be noted that the jack herein described, when not in use, is housed under the body but can at all times be conveniently reached.

What is claimed is:—

1. The combination with a vehicle body and a wheel supported axle connected thereto, of a bail-like jack mounted to swing upon the axle, an elongated coiled spring secured at one end to the free end of the jack and extending loosely under the axle and secured at its other end to the vehicle, said spring constituting means for drawing the jack downwardly into contact with the supporting surface and for shifting it rearwardly past its center of gravity when the vehicle is raised, a stop device upon the axle for limiting the rearward movement of the jack past its center of gravity, and a fastening

device for engaging the jack to hold it in inactive position.

2. The combination with a vehicle body and wheel supported axles connected thereto, of a bail-like jack mounted to swing upon each axle, means upon the free end of each jack for engaging the surface on which the vehicle is mounted, a spring extending under each axle and secured at one end to the adjacent jack and at its other end to the vehicle, fastening devices for engaging the jacks and holding them inactive, said springs constituting means for shifting the jacks, when released, downwardly into contact with the supporting surface and for shifting said jacks rearwardly past their centers of gravity when the vehicle is elevated, and a stop device upon each axle for engagement by the adjacent jack to limit the rearward movement of the jack.

In testimony that I claim the foregoing as my own, I have hereto affixed my signature in the presence of two witnesses.

WILLIAM M. LEWIS.
